TIMER

Earle G. Henry, Wilmette, Ill., assignor to Buckley
Music System, Inc., a corporation of Illinois

Application February 18, 1944, Serial No. 522,919

3 Claims.

(Cl. 74—54)

There is a common form of timing device wherein one or more elements that actuate or carry switches or other things are rocked back and forth by a revolving cam shaft; separate cams being employed for each element, when their timings are required to be different. Such devices have been unsatisfactory in some respects on account of limitations imposed by the cams. While a cam roller can drop abruptly from a high section of a cam to a low section, the reverse is not true; a gradual slope being required between two such cam sections to enable the roller to climb uphill. Therefore the rocking movement of the driven element is necessarily slow in one direction. If the work that the rocking element is to do is to open and close a switch, for example, serious arcing may occur due to slowness in opening the switch, even if it be a mercury switch. Also, because of the considerable length of time required for a cam roller to shift fully from the low section of the cam to the high section, the interval of time between leaving the high section and again returning to it must always be a substantial one, particularly in the case of a very slowly rotating cam shaft. Consequently, if a switch, for example, is in a closed position while the cam roller is on the low section of a cam, it cannot be opened immediately after being closed, but only after the roller has had time to ascend a gradual slope; thereby placing an undesirable limitation on the possible range of ratios between the time that the switch may be open and the time that it may remain closed in each cycle of operations.

The present invention has for its object to produce a simple and novel timer construction in which the driven or controlled member is shifted speedily from each of its two positions to the other and may return from one of such positions to the other after being there for practically the shortest measurable time, if desired.

The various features of novelty whereby my invention is characterized will hereinafter be pointed out in the claims; but, for a full understanding of my invention and of its objects and advantages, reference may be had to the following detailed description taken in connection with the accompanying drawings, wherein:

Figure 1 is a front view of a fragment of a panel having thereon one of my timers; Fig. 2 is a section on line 2—2 of Fig. 1; Figs. 3, 4 and 5 are sections on line 3—3 of Fig. 1, showing the parts in three different positions; Fig. 6 is a section on line 6—6 of Fig. 1; Figs. 7 and 8 are a side view and an edge view of one of the cams

visible in Fig. 6; and Figs. 9 and 10 are a side view and an edge view of the second cam seen in Fig. 6.

In the drawings I have illustrated my invention in an apparatus wherein the controlled member, that is the member whose movements are to be timed, carries a switch or switches; and, for the sake of brevity, the detailed description will be confined to this particular embodiment, as the alterations needed to adapt the device to other uses or to other manner of uses can easily be made.

Referring to the drawings, 1 and 2 are like switch carriers mounted so as to be capable of moving back and forth through a limited distance between two working positions. In the arrangement shown, these members are sturdy metal plates, more or less rectangular in shape, supported on a stationary, horizontal shaft 3 for rocking movements independently of each other in parallel, vertical planes. These elements, as well as the shaft 4, below, a little in front of and parallel to the shaft 3, have long been used in a timer to which my invention can readily be applied; the number of switch carriers depending on the number of switches to be operated. The shaft 4, which is a cam shaft, is shown as being driven from a drive or timing shaft 5 by a pinion 6 on the latter meshing with a gear 7 on the cam shaft; the shaft 5 being conveniently driven, as heretofore, by a constant speed motor, not shown. The shafts 3 and 4 are shown as being supported in suitable brackets 8, 8 on a base member 9 that is in turn mounted on a suitable panel, 10.

Mounted on the shaft 3, beside but spaced a short distance apart from each of the switch carriers or controlled members is a dog or controlling member 11 capable of rocking independently of each other and of the carriers. On each carrier, forwardly of the shaft 3, is a pin 12 that projects across the plane of the corresponding dog, so that when the latter assumes a predetermined angular position relative to its switch carrier its forwardly extending arm contacts the pin. A tension spring 14 extends between and is connected at its ends to a pin 15 on the other arm of the dog and a pin 16 on the switch carrier. The parts are so arranged that the spring 14 of each unit yieldingly holds its dog in contact with the pin or stop shoulder 12 on the adjacent switch carrier, when free to do so. Associated with each of the two units is a second spring 17 which extends between and is connected at its ends to the pin 15 and a pin 18 projecting from the front side of the base 9.

On the cam shaft are two sets of cams, one for each unit, each set including a cam cooperating directly with the corresponding switch carrier and a second cam that acts on the dog or controlling member for that carrier. The cams that act on the switch carriers are shown as being composed of two mutilated disks, 19 and 20, lying face to face and secured together by screws 21 passing through holes 22 in the members 19 into the members 20. The parts are so proportioned that each of these cams may have a peripheral high section in the form of an arc of a circle having a minimum angular length of about one hundred and twenty degrees and a maximum angular length of about two hundred and forty degrees, depending on the angular adjustment of the two disks, relatively to each other; the remainder of the periphery being the low section of the cam. One end of the low section terminates at a radial shoulder 24 which meets the adjacent end of the high section of the cam, while the other end of the low section merges into a gradual upward slope 25 which, in turn, merges with the high section. The second cam of each set may be a single mutilated disk 26 having a peripheral arc-shaped high section 27 of about two hundred and ten degrees joined at one end to a low section by a radial slope 28, whereas a gradual slope 29 joins the other ends of the two sections together. The aforesaid angular lengths are given by way of example and may, of course, be altered to suit conditions to be met. This is also true with respect to the angles of the slopes that connect the high and low sections of the cams together.

Each of the switch carriers has thereon a cam roller 30 cooperating with the two-piece or double cam; and each rocking dog is provided with a cam roller 31 that is at all times in engagement with the corresponding cam 26.

The cam shaft is driven in the clockwise direction as viewed in Fig. 2 and in the counter clockwise direction as viewed in Figs. 3, 4, 5 and 6.

The member 1 is shown as having a single mercury switch A mounted thereon, while there are two such switches B and C, on carrier 2. The switches A and B close when their carriers are rocked forward and open when the carriers are rocked into their rearward positions.

The operation will now be explained. It will be seen from Figs. 2 and 3, which indicate like positions of all parts, looking at the unit at the left hand end in Fig. 2, that the carrier 1 is in its rearward position, the switches A and B being open and the switch C being closed. The cam roller 30 is resting on the high section of the double cam and the cam roller 31 is on the high section of cam 26. It will be seen that as the cam shaft turns in the direction of the arrows in these figures, no change in the positions of the switch carriers and rocking dogs occurs until the abrupt slope 24 moves past the cam roller 30. Then, however, this roller snaps down on the low section of the cam, the spring 14 goes into action to swing the carrier forward, and the cam roller 31 still remains on the high section of its cam. The parts are now in the positions indicated in Fig. 4. Because it is assumed that switch A is to remain closed only a very short time, the cam roller 31 is very close to the abrupt slope on its cam but still is supported on the high part of the cam. During all this time the spring 17 has been under a maximum tension so that, when the cam roller 31 reaches the abrupt slope 28, this spring rocks the dog in the clockwise direction as viewed

in Fig. 4 and causes it to drive the carrier 1 to the rearward position, as seen in Fig. 5. As the rotation of the cam shaft continues, the gradual upward slope 25 on the double cam reaches the cam roller 30 and causes it to ride up until it rests on the high section of the cam. This locks the switch carrier against forward movement until the abrupt slope 24 again reaches the cam roller 30 and allows it to drop. After the member 1 has been made secure with the switch in its open position, the incline 29 on the cam 26 engages the cam roller on the dog 11, causing the dog to rock in the counter clockwise direction from the position occupied in Fig. 5 to that in Fig. 3 where the dog is shown rocked down away from the pin or shoulder 12 on the switch carrier. This movement of the dog stretches the spring 14 which is then free to snap the carrier forward, without interference on the part of the dog when the cam roller 30 is again in position to drop off the high section of the double cam, as in Fig. 4.

The cams are provided with hubs 33 and 34, respectively, which may be fixed to the cam shaft by set screws 35. Upon loosening the set screws the cams may be shifted angularly of the cam shaft, to adjust them, and then be secured by again tightening the screws. The period for which the switch remains closed may thus be varied both by changing the relative angular positions of the two cams and by making the adjustments required to change the length of the high section of the double cam. Thus, the unit having associated therewith the two switches, B and C, has the high section of its double cam shortened through the adjustment of the two disks angularly of each other; while, as shown in Fig. 6, the cam 26 of this unit is not quite in the same angular position relative to the double cam as is the case in the first unit. As previously stated, the construction of the corresponding cams in the two units is the same, so that Figs. 7 to 10 of the drawings may be said to illustrate either set, although showing the adjustments, as they appear in Fig. 6, of the cams in the second unit which contains the switch carrier.

Whether a switch be opened or closed when a carrier is rocked in one direction or the other depends, of course, on which end thereof is on the front side. Thus, in the second unit, the switches B and C are so disposed that whenever one is open the other is closed.

While any suitable means may be employed to keep the controlled members and the controlling members properly spaced on their supporting shaft, sleeves 36 of insulating material and sheaves 37, also of insulating material and adapted to serve as guides for leads (not shown) to the switches may be used.

In the particular construction illustrated provision is made for only three different relative angular positions of the two disk-like elements of the two-piece cam. However, because of the proportions which the two cams have and of the capacity for adjustment of the cams bodily, angularly with respect to each other, any desired timing cycle may be obtained. At the same time, when the fastening screws are tightened, the two members of the double cam are locked together solidly in such a way that accidental relative angular displacement during use is impossible.

The most important feature of my invention, it will be perceived, is that the controlled member is permitted to move rapidly from one extreme position to the other in the same manner as would be the case if it were possible to con-

struct a single rotatable cam that could shift a roller from a low section to a high section as rapidly as a roller can drop in the opposite direction. The rapidity of the shift is determined solely by the needs of the service to be rendered. Thus, in the example illustrated, the mercury switches should be shifted rapidly but, also, gently, to avoid the creation of oscillatory movements of the mercury at the end of a shifting movement of the same. Consequently, the movement of the cam rollers down the steep slopes of the double cams should be checked a little; whereas, on the other hand, since the single cams do not act directly on the switch carriers, the dropping of the rollers on the rocking dogs or controlling members may be instantaneous if desired.

While I have illustrated and described with particularity only a single preferred form of my invention, I do not desire to be limited to the exact structural details so illustrated and described; but intend to cover all forms and arrangements coming within the definitions of my invention constituting the appended claims.

I claim:

1. A controlled member whose movements and periods of rest are to be timed, a controlling member, said members being mounted side by side for independent movements back and forth, a shoulder on the controlled member in position to be engaged by the controlling member when the latter is moved into a predetermined position relative to the other member, a spring connecting said members together and tending constantly yieldingly to hold the shoulder and the controlling member in engagement with each other, a second spring tending constantly to move the controlling member in the direction to drive the controlled member to a predetermined rearward position, two cams rotatable in unison with each other, one cam cooperating with the controlled member and having such a contour that it lifts and then locks that member in said predetermined rearward position during a predetermined

part of each revolution and then abruptly leaves it free to return to a predetermined forward position, and the other cam acting on the controlling member and having such a contour that during a predetermined part of each revolution it moves the controlling member into and holds it in a retracted position and then abruptly leaves it free to move in the direction to drive the controlled member into the vicinity of the said predetermined rearward position of the latter.

2. A controlled member whose movements and periods of rest are to be timed, a controlling member, said members being mounted side by side for independent movements back and forth, a shoulder on the controlled member in position to be engaged by the controlling member when the latter is moved into a predetermined position relative to the carrier member, a spring connecting said members together and tending constantly yieldingly to hold the shoulder and the controlling member in engagement with each other, a second spring tending constantly to move the controlling member in the direction to drive the controlled member to a predetermined rearward position, two cams rotatable in unison with each other, each cam having a high section and a low section, the trailing end of the high section of each cam dropping abruptly to the low section and the trailing end of each low section being connected to the corresponding high section by a gradual slope, and a cam roller on each of said members in operative relation to one of the cams.

3. A construction such as set forth in claim 2, wherein the cam that cooperates with the controlled member is adjustable with respect to the relative lengths of the high and low sections, whereas the other cam has a high section about as long as the maximum length of the high section of the first cam and a low section about equal to the minimum length of the high section of the first cam.

EARLE G. HENRY.
